(57) **CLAIM**

The ornamental design for a handle for lawn fork, as shown and described.

DESCRIPTION

FIG. 1 is a perspective view of a handle for lawn fork showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a perspective view thereof, shown in an alternate state;

FIG. 9 is a perspective view thereof, shown in another alternate state; and,

FIG. 10 is a perspective view thereof, shown with environment.

The broken lines illustrate portions of the handle for lawn fork that form no part of the claimed design. The broken lines showing a lawn fork in FIG. 10 are for the purpose of illustrating environmental structure, and form no part of the claimed design.
